UNITED STATES PATENT OFFICE.

HERMAN GASSTROM, OF NEW YORK, N. Y., ASSIGNOR TO DAHL MANUFACTURING CO.,
A CORPORATION OF NEW YORK.

INTERLOCKING SLIDABLE SECTIONS.

1,288,556.

Specification of Letters Patent. Patented Dec. 24, 1918.

Application filed January 31, 1916. Serial No. 75,257.

To all whom it may concern:

Be it known that I, HERMAN GASSTROM, a subject of the Czar of Russia, residing in the county, city, and State of New York, have 5 invented certain new and useful Improvements in Interlocking Slidable Sections, of which the following is a specification.

This invention relates to an improvement in rules made up of a plurality of slidable 10 interlocking sections. My invention pertains more particularly to a specially formed locking mechanism by which means the sections of the rule are locked in closed and in extended positions.

15 In the drawings which form part of this specification

Figure 1 is a top plan view of a sectional rule, one end of one section being broken off;

20 Fig. 2 is a side view thereof;

Fig. 3 is an enlarged cross sectional view, the section being taken on a line 3—3 in Fig. 2;

25 Fig. 4 is a top plan detail view of my improved support for the locking tongue for the rule sections;

Fig. 5 is a sectional view thereof, the section being taken on a line 5—5 in Fig. 4;

30 Fig. 6 is an enlarged view of one of the locking tongues;

Fig. 7 is an enlarged cross sectional view thereof, the section being taken on a line 7—7 in Fig. 6;

35 Fig. 8 is an enlarged plan view of one end of one of the rule sections, showing the tip therefor;

Fig. 9 is a sectional view thereof, the section being taken on a line 9—9 in Fig. 8;

40 Fig. 10 is an enlarged longitudinal sectional view of some of the rule sections in closed position;

Fig. 11 is a similar view illustrating the manner of extending the rule sections.

The rule herein illustrated consists of a 45 plurality of sections, A, B, C and D, which are slidably connected by plates 1 and 2, each of the plates 1 being provided with guides in the form of bent over flanges 3, Fig. 3, which engage slots 4 in the sections 50 of the rule, and also with flanges 5 which are forced into contact with the sections to hold the plates in place. For instance, the section B, at one end thereof, carries a plate 1, see Fig. 3, the flanges 5 of which

grip said section, while the flanges 3 engage 55 the slots 4 in the section A. The section A carries a plate 2^a (see Figs. 1 and 10 at the left end thereof), the flange 11 of which grips the said section while the flange 12 engages the slot 4 in the section B. By 60 these means all of the sections A, B, C and D are slidably connected. Each plate 2 on the sections B, C and D carries ears 6 which pivotally support a tongue 7, each tongue operating within a pocket 8 in said sections. 65 All of the sections, excepting section A are locked together by tongues 9 carried by the plates 1, each tongue 9 operating in a pocket 10 in said sections. The section A is a master section by which means the opening or 70 closing of the sections is controlled. The section A at the right end thereof carries a plate 2^a having the flanges 11 referred to, which secure the plate to the said section, said plate 2^a having no interlocking function, but being merely to guide the section A (see Fig. 1). When slid along the section B, the flange 12 also referred to of the plate 2^a engages the slot 4 in the section B. 75

Each tongue 7 carries a nose 14, which is 80 adapted to pass through an opening 15 in a guard plate 16 carried by each section, and when the sections are extended, these ends 14 will project through the said openings, as shown in Fig. 11, in which figure 85 the section A is extended sufficiently to unlock the sections B and C.

When the rule is fully extended, each nose or end 14 will project through its opening 15. Hence, when the rule is to be closed the 90 tongues 7 will be automatically unlocked by the movement of the sections one upon the other.

As shown in Fig. 10, the sections of the rule are locked in closed position, that is to 95 say, the rule cannot be extended without the use of force, because the nose piece 14 of each tongue 9 will prevent the sections from sliding one upon the other, excepting section A. When the sections are closed each 100 nose-piece 14 enters alining openings 17 and 18 in a guard plate 19 and plate 1 respectively. The movement of the sections, one upon the other, is prevented, when said sections are closed, by the contacting of the 105 said nose-pieces 16 and rear wall 20 of said openings 18. The tongues 7 act to unlock the tongues 9, or force them partly out of

the openings 18, while the sections are being extended, as will hereinafter be described.

To extend the rule, the section A will be moved toward the left (see Fig. 11) until 5 the tail-piece 21 of the tongue 7, carried thereby, is forced through an opening 22 in the underlying plate 1 by the spring member 23, which is an extension of the nose-piece 14, the said spring member pressing against the 10 plate 2. When the tail-piece 21 alines with the opening 22, it will be forced therethrough by the spring member 23, finally striking the elevated end 24 of the tongue 9, carried by the section B, and raising the 15 nose end 16 thereof partly out of the opening 18, or at least enough to permit the inclined front wall 25 of the opening 18 to further raise the end 16 of the tongue when the section B is moved along the section C. 20 When the section B is moved toward the left, after the section A has been moved to partly unlock the tongue 9, as has been described, the end 16 of the tongue 9 will ride up the inclined wall 25 very easily without 25 necessitating a strong pull upon the section. This form of wall is preferable to a straight or abrupt wall, as the latter causes an impediment to the easily sliding motion of the rule members when they are opened.

30 After the section B has been extended, the section C will become unlocked in the manner described and may be extended. Each rule section unlocks the next underlying section, and each rule section, excepting the top 35 section, which is the master section, or the section which controls the opening or closing of the rule sections, carries a locking tongue and a tongue to operate the locking tongue of an underlying section.

40 The foregoing statement is merely an outline of the operation of the rule, as the operation and construction thereof is fully set forth in United States Letters Patent No. 1,159,012 issued to me, and bearing the date 45 of November 2nd, 1915.

The object of this improvement, which has been referred to in connection with the rule, is to provide means to facilitate the operation of the locking tongues after they 50 have been partly released, the said means being in this instance the inclined wall 25.

The inclined walls 25 will force the ends 55 of the tongues 9 inwardly against the tension of the spring members 26, which are extensions of the ends 16. Each plate 1 carries ears 27 which pivotally support the locking tongues 9.

The whole function of the walls 25 is to still further raise the ends 16 or locking 60 ends of the tongues 9 after they have been for the most part, unlocked by the tongues 7, to permit the rule sections to be easily moved one upon the other.

To insure a perfect lock, it is necessary 65 that the spring member 26 be comparatively

stiff, consequently the members 23 of the tongues 7 will not have enough spring tension to completely unlock the said tongues 9, and for the perfect operation of the rule, the ends 16 of the tongues must be raised 70 to aline with the outer face of the plates 1, which result is accomplished by the walls 25.

A further feature of the device is the formation of the tongues 7 and 9 to provide 75 rounded trunnions 28 (see Fig. 6). To produce the rounded trunnions, I emboss the said tongues, or force part of the metal thereof upwardly as at 29 and 30, Figs. 4, 6 and 7, the extensions or trunnions formed by the striking up process being rounded 80 and thereby fitting the round openings in the ears 27.

A further feature of improvement consists of a tip for the section A, which is designed to be applied to one end of the section in 85 such manner as to prevent the splitting of the wood. This tip consists of thin metal plate 31 bent over to form a top and bottom member 32 and 33, each of said members being provided with an inwardly directed flange 34, arranged to fit a previously 90 formed groove 35. By means of this formation I am able to apply the tip without resorting to any means to puncture the wood or to be forced into the wood, as the end of 95 the section is previously prepared to receive the tip.

Having thus described my invention, what I claim and desire to secure by Letters Patent is:

1. In a device comprising a plurality of 100 slidably connected members arranged for extension, means carried by one section other than the first section to interlock with an underlying section, when said sections are 105 folded, means carried by said one section to partly unlock said interlocking device, while said members are being extended and auxiliary means carried by the underlying section to complete the unlocking of the interlocking 110 device.

2. In a device comprising a plurality of 115 slidably connected superposed members arranged for extension, means carried by each section except the first to lock said sections together when said sections are closed, means carried by each section except the last to partly unlock the locking device for an underlying section, and an angularly disposed wall adjacent each locking device to 120 complete the unlocking operation while the members are being extended.

3. In a device of the character described, a plurality of superposed slidable members arranged for extension, locking means carried by each member excepting the first to engage an underlying member and lock said members together when said members are closed, means carried by the first member to initiate the unlocking operation when said 130

first member is moved in the proper direction, and means carried by the underlying sections to complete the unlocking operation.

4. In a device of the character described,
- 5 a plurality of slidable members arranged for extension, a plate carried by each section excepting the last slidably engaging and underlying section having an opening therein, a locking device carried by each plate except
- 10 the last to engage the opening in the plate of an underlying section, and means adjacent the opening in each plate to engage the locking device in engagement with said opening arranged to force the locking device
- 15 out of the opening when the slidable members are moved in the proper direction.

5. A rule member provided near the end thereof with transversely disposed curved

grooves, there being a groove in each face of the member, a tip for said rule consisting of 20 a plate bent over to form top and bottom members for the end of said rule member, and a curved flange at the end of the bent over portions of said plate to engage the transversely disposed grooves in the rule 25 member, whereby said tip is prevented from movement transversely of the rule member, and also movement longitudinally thereof.

Signed at New York city, N. Y., this twenty-eighth day of January, one thousand nine hundred and sixteen.

HERMAN GASSTROM.
